UNITED STATES PATENT OFFICE

BENJAMIN F. MIESSNER, OF SHORT HILLS, NEW JERSEY, ASSIGNOR, BY MESNE ASSIGNMENTS, TO RADIO CORPORATION OF AMERICA, OF NEW YORK, N. Y., A CORPORATION OF DELAWARE

RADIO RECEIVING SYSTEM

Application filed July 20, 1929. Serial No. 379,672.

This invention relates to radio receiving systems and particularly those employing a number of stages of radio frequency amplifiers in cascade and energized by sources of fluctuating unidirectional current.

In energizing a radio frequency amplifier from a source of fluctuating potential, such as a poorly filtered output of a rectifier supplied from a 60 cycle alternating current supplied by most commercial generating plants of the present day, there results a modulation of signal currents received from a broadcasting station and amplified by such an amplifier.

The problem of how such modulation can be obliterated without distorting the signal currents is complex and therefore requires at least a brief summary of the various reactions occurring in a radio receiver when energized from a source of fluctuating potential.

In a radio receiving system having one or more radio frequency amplifier stages, a detector, and one or more audio frequency amplifier stages in cascade, or reflexed, when no signal is being amplified by the radio frequency stage, low frequency of the order of 60 cycles or harmonics thereof will not be transferred to the detector through the radio frequency transformer. Therefore, the system in this condition must be neutralized for hum components developed by the detector and audio stages of amplification.

When a receiver, non-receptive of signals, is neutralized so that no hum is heard in the loud speaker and then a signal is tuned in, it will be noted that there is an accompanying hum developed along with the audible signals. This is especially true of a system in which the filter system has been reduced to a point insufficient for the load placed thereon.

I have described in a number of copending applications methods by which this hum accompanying the signal in the loud speaker may be eliminated by re-neutralizing the system while operating during the reception of signals.

In such systems I have found the objection that while no signal is being received there

is hum developed in the loud speaker, a feature objectionable to some users thereof. However, the primary objection that I find is that the modulation of the high frequency currents by the fluctuating energization of the radio frequency tubes is variable as a function of the intensity of the signal so that if the system is re-neutralized with a received carrier wave of average strength, hum will develop in the loud speaker on signals stronger or weaker than that for which it was neutralized, and this hum is variable as a function of the variation in the intensity from the predetermined standard.

It is the object of this invention to neutralize the modulation of the carrier wave by the fluctuating energization of the radio frequency tubes within the radio frequency systems without radio frequency regeneration being caused thereby.

Two modifications are shown in the accompanying drawings in which like reference characters indicate corresponding parts throughout, insofar as possible.

Referring to the drawings VT designates a vacuum tube, the input circuit of which includes the secondary RS₁ of a radio frequency transformer RT₁, tunable by means of a variable condenser VC₁. The primary RP₁ of the transformer RT₁ is so connected that it has flowing therein carrier currents modulated at audio frequency, for example as being included in an antenna circuit or constituting the output coil similar to RP₂ of a preceding radio frequency stage, the circuits of which are similar to those to be hereinafter described.

The output circuit of the tube VT includes the primary RP₂ of a radio frequency transformer RT₂, the secondary RS₂ of which is tunable by means of a variable condenser VC₂. The filament of the tube VT is heated from a source of alternating current through a filament heating transformer HT, the secondary HS of which is shunted by a center tap potentiometer CT.

In the circuit of Fig. 1, the plate-filament circuit of tube VT is energized from a source of fluctuating potential S, such as a rectifier, the output filter of which is shunted by a

filter condenser FC in a well known manner.

The low potential terminal of the source S is connected to the center tap CT through the primary AP₁ of an iron core transformer AT₁ having a high step-up ratio, and through a biasing resistance BR series related. The high potential terminal of the source S is connected to the plate of the tube VT through the primary RP₂ of the transformer RT₂.

I have provided a connection between the grid of tube VT through the secondary RS₁ and the secondary AS₁ to the low potential terminal of the bias resistor BR.

In Fig. 2, I have shown the modification of the system in that the low potential terminal of the source S is connected through the secondary AS'₁ of the high step-up ratio iron core transformer AT', to the center tap CT, and have included the primary AP'₁ in the connection between the high potential terminal of the source S and the primary RP₂. I have connected the grid of the tube VT through the secondary RS₁ to the low potential terminal of the source S, the potential drop across the resistance of the secondary AS'₁ serving to maintain the average potential of the grid of tube VT negative with respect to its filament.

In each of the systems I have by-passed the radio frequency currents in the grid and plate circuits around the energizing system by means of radio frequency by-pass condensers C₁ and C₂ respectively.

In each of the systems the windings of the transformers AT₁ and AT', are so selected in ratio and so poled that the plate current of the tube VT is rendered devoid of any fluctuation in current due to the fluctuating potential energization thereof, so that the carrier currents are transferred from the primary RP₁ to the resonant secondary RS₂ in amplified form without being modulated at hum frequencies.

It will be noted that in the foregoing description I have limited my description to radio frequency stages, this because such a structure, if applied to audio frequency stages, would produce degeneration of the audio frequency signal currents through the action of the transformers AT₁ and AT', upon the grid circuit of the tube VT.

It will be understood that minor detail changes may be made in the systems described herein without departing from the spirit of my invention as defined in the appended claims.

Having thus described my invention I claim:—

1. In a radio frequency amplifying system, the combination of a vacuum tube having input and output circuits, a source of fluctuating unidirectional current, connections for energizing the plate and grid electrodes from said source, and means within the grid-filament and plate-filament circuits of said tube for

varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube the windings of said primary and secondary being relatively proportioned and poled to produce said tube impedance variation.

2. In a radio frequency amplifying system, the combination of a vacuum tube having input and output circuits, a source of fluctuating unidirectional current, connections for energizing the plate and grid electrodes from said source, means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube the windings of said primary and secondary being relatively proportioned and poled to produce said tube impedance variation, and means for by-passing the radio frequency currents directly from said input and output circuits to the cathode of said tube.

3. In a radio frequency amplifying system, the combination of a vacuum tube having input and output circuits, a source of fluctuating unidirectional current, connections for energizing the plate and grid electrodes from said source, and means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube the windings of said primary and secondary being relatively proportioned and poled to produce said tube impedance variation, the potential developed across the secondary of said transformer determining the average potential of the grid of said tube relative to the cathode thereof.

4. In a radio frequency amplifying system, the combination of a vacuum tube having input and output circuits, a source of fluctuating unidirectional current, connections for energizing the plate and grid electrodes from said source, and means within the grid-filament

ment and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube, the secondary of said transformer also series related within the plate-filament circuit of said tube, whereby the average potential of grid of said tube is determined by the potential drop across said secondary and the windings of said primary and secondary being relatively proportioned and poled to produce said tube impedance variation.

5 20 5. In a radio frequency amplifying system, the combination of a vacuum tube having input and output circuits, a source of fluctuating unidirectional current, connections for energizing the plate and grid electrodes from said source, and means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube, the secondary of said transformer also series related within the plate-filament circuit of said tube, whereby the average potential of grid of said tube is determined by the potential drop across said secondary and the windings of said primary and secondary being relatively proportioned and poled to produce said tube impedance variation, and means for shunting the radio frequency currents from said input and output circuits to the cathode of said tube around the primary and secondary of said transformer.

6. In a radio frequency amplifying system, the combination of a vacuum tube having input and output circuits, a source of fluctuating uni-directional current, connections for energizing the plate and grid electrodes from said source, and means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube, the secondary of which is series related within the plate-filament circuit of said tube, whereby the average potential of grid of said tube is determined by the potential drop across said secondary and the windings of said primary and secondary being relatively proportioned and poled to produce said tube impedance variation, the potential developed across the secondary of said transformer determining the average potential of the grid of said tube relative to the cathode thereof, and a radio frequency by-pass condenser connected across said primary and secondary.

windings of said primary and secondary being relatively proportioned and poled to produce said tube impedance variation, and a grid biasing resistor connected between the cathode of the tube and said secondary.

7. In a radio frequency amplifying system, the combination of a vacuum tube having input and output circuits, a source of fluctuating uni-directional current, connections for energizing the plate and grid electrodes from said source, and means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube, the windings of said primary and secondary being relatively proportioned and poled to produce said tube impedance variation, and means for by-passing the radio frequency currents directly from said input and output circuits to the cathode of said tube, and a grid biasing resistor connected in series between the said secondary and the cathode of said tube.

8. In a radio frequency amplifying system, the combination of a vacuum tube having input and output circuits, a source of fluctuating uni-directional current, connections for energizing the plate and grid electrodes from said source, and means within the grid-filament and plate-filament circuits of said tube for varying the impedance of said tube in consonance with the fluctuations of said source whereby high frequency currents are amplified by said tube without modulation thereof by said source, said means consisting of a transformer, the primary of which is series connected within the plate-filament circuit of said tube, and the secondary of which is series connected within the grid-filament circuit of said tube the windings of said primary and secondary being relatively proportioned and poled to produce said tube impedance variation, the potential developed across the secondary of said transformer determining the average potential of the grid of said tube relative to the cathode thereof, and a radio frequency by-pass condenser connected across said primary and secondary.

In witness whereof, I have hereunto subscribed my name this 17th day of July, 1929.

BENJAMIN F. MIESSNER.
